UNITED STATES PATENT OFFICE.

HANS CHRISTIAN JORGENSEN, OF MONTREAL, QUEBEC, CANADA.

FLOAT.

1,143,830.

Specification of Letters Patent. Patented June 22, 1915.

Application filed July 25, 1914. Serial No. 853,169.

To all whom it may concern:

Be it known that I, HANS CHRISTIAN JORGENSEN, a subject of the King of Great Britain, and resident of Montreal, Province of Quebec, Canada, have invented certain new and useful Improvements in Floats; and I do hereby declare that the following is a full, clear, and exact description of the same.

10 This invention relates to floats which are carried by vessels for the preservation of life in the event of the sinking of the vessel or other emergency and an object is to provide a simply constructed float which occupies

15 a small space and can be conveniently stored upon the decks of the vessel.

Another object is to so construct the float that a number of the same can be readily and quickly secured together to form a large

20 float or raft.

For full comprehension, however, of my invention reference should be had to the accompanying drawing forming a part of this specification in which similar reference 25 characters indicate the same parts and wherein:

Figure 1 is a plan view, partly in section, of a raft composed of a number of my improved floats; Fig. 2 is a side elevation thereof, partly in section; Figs. 3 and 4 are respectively enlarged side and plan views of portions of adjacent floats and illustrating particularly the connection between 30 same; and Fig. 5 is an enlarged perspective view of one of my improved floats.

Referring now to the drawings, my improved float consists of a hollow, air-tight member 2 preferably formed of metal and braced by exterior bands 3 which extend 40 about the member from side to side thereof and cross at right angles to each other at about the middle of the float, at which point such bands are secured together and to the float by a bolt 4 and nut 5, the bolt 45 extending through both bands and from top to bottom of the member, the portion of the bolt passing through the interior of the float being inclosed by a sleeve 6 which constitutes a distance piece, the ends of which 50 respectively bear against the top and bottom interior surfaces of the member 2. A rail 7, preferably formed of pipe, is located around the sides of the float preferably midway between the top and bottom levels of the latter, the rail being supported by brackets

8 which are riveted or otherwise suitably fastened upon the bands 3. The brackets extend some distance out from the sides of the float 2 so that a space is provided between the latter and rail enabling the latter 60 to be readily grasped. As the air space of the float extends substantially completely across the complete area of the latter it will be seen that the maximum upholding capacity is obtained while as the member 2 65 normally floats high in the water as illustrated in Fig. 2, the position of the rail 7 provides that the same can be readily grasped by a person in the water.

The float is flat as shown particularly in 70 Fig. 5 and consequently a large number can, without inconvenience, be stored against the rails of a vessel in readiness to be thrown overboard or floated off.

For convenience in use and conveyance 75 from place to place, the floats are preferably of small size but to enable a float of large size to be formed when desired I have provided means for connecting any number of my improved floats together. These means 80 consist preferably of eyes 9 secured to and extending outwardly from each side portion of the rails 7 of the floats, the position of the eyes of each float preferably being such that when two floats are brought into 85 substantial alinement the eyes of one float will register with those of the other.

When the composite float is being formed the several small floats are brought side to side (Fig. 1) and the eyes upon the adjacent sides of each unit are brought into 90 register with those of another unit and coupled by means of headed pins 10.

Each of the pins 10 are transversely bored 95 and adapted to have a cotter 11 passed therethrough to secure them against accidental displacement while to avoid loss of the pins and cotters and to constantly maintain them ready to hand they are secured to the float or rail by flexible lengths 12.

What I claim is as follows:—

1. A float consisting of a hollow air-tight member, bands extending about the exterior of the member and crossing each other at the middle of the latter, a bolt passing 105 through the crossed bands and extending from top to bottom of the hollow member, a sleeve inclosing the bolt and bearing at its ends respectively against the top and bottom interior surfaces of such member, sup- 110

- ports secured to the exterior sides of the hollow member, a rail carried by such supports and spaced from the sides of the member.
- 5 2. A float consisting of a plurality of hollow, air-tight members, rails secured to and spaced from all the sides of the members, eyes secured to and extending rigidly from said rails, the eyes of each hollow member
10 registering with the eyes of another hollow

member, pins inserted through the eyes and cotters passed through said pins.

In testimony whereof, I have signed my name to this specification, in the presence of two subscribing witnesses.

HANS CHRISTIAN JORGENSEN.
